UNITED STATES PATENT OFFICE

133,783

DESIGN FOR A SAFETY DEVICE FOR HYPODERMIC NEEDLE

Franklin Porter, Chicago, Ill.

Application August 1, 1941, Serial No. 102,628

Term of patent 14 years

To all whom it may concern:

Be it known that I, Franklin Porter, a citizen of the United States and a resident of Chicago, in the county of Cook and State of Illinois, have invented a new, original, and ornamental Design for a Safety Device for Hypodermic needle, of which the following is a specification, reference being had to the accompanying drawing, forming a part thereof, and in which:

Fig. 1 is a perspective view of a safety device for hypodermic needle showing my new design;

Fig. 2 is a side elevational view of the safety device for hypodermic needle shown in Fig. 1 and at a slightly larger scale with respect thereto;

Fig. 3 is an end elevational view of the same as seen from the left in Fig. 2; and

Fig. 4 is an end elevational view of the same as seen from the right in Fig. 2.

I claim:

The ornamental design for a safety device for hypodermic needle, as shown.

FRANKLIN PORTER.
